UNITED STATES PATENT OFFICE.

FREDERICK O. KILGORE, OF BOSTON, MASSACHUSETTS, ASSIGNOR TO SPRAY PRIMER COMPANY, OF BOSTON, MASSACHUSETTS, A CORPORATION OF MASSACHUSETTS.

PRIMER.

1,233,247.

Specification of Letters Patent. Patented July 10, 1917.

Application filed December 28, 1916. Serial No. 139,384.

To all whom it may concern:

Be it known that I, FREDERICK O. KILGORE, a citizen of the United States, and a resident of Boston, in the county of Suffolk 5 and State of Massachusetts, have invented an Improvement in Primers, of which the following description, in connection with the accompanying drawings, is a specification, like characters on the drawings representing 10 like parts.

This invention relates to an apparatus for priming internal combustion motors, and has for its object to provide a simple, efficient and inexpensive apparatus, which is 15 especially applicable to automobiles, motor cycles, motor boats and the like.

The apparatus consists essentially of a pump provided with a cylinder and a piston reciprocating therein, and said piston in accordance with the present invention has connected with it a valve, which controls communication between the said cylinder and an outlet passage designed to be connected with the motor to be primed, said valve being arranged to cut off the cylinder from said outlet passage on the suction stroke of the piston in said cylinder and to seal the gasoline in the cylinder against the action of the motor. The valve may and preferably will also coöperate with a fluid inlet for the cylinder, as will be described. These and other features of this invention will be pointed out in the claims at the end of this specification.

Figure 1 represents a portion of an automobile provided with a priming apparatus embodying this invention.

Fig. 2, a longitudinal section of the apparatus with the piston at the end of its suction stroke.

Fig. 3, a like section with the piston near the end of its discharging stroke, and

Fig. 4, a section on the line 4—4, Fig. 2.

Referring to the drawing, *a* represents the cylinder of a pump, which is provided 45 at one end with the head *b* and between its ends with a transverse wall or head *c*, and at its opposite end with a removable cap *d*. The transverse wall or head *c* coöperates with the head *b* and cap *d* to form chambers 50 10, 12 on opposite sides of the wall *c*, which are in open communication with each other by means of openings 13, extended through the wall *c*, see Fig. 4.

The wall *c* is also provided with a central 55 opening 15 through which is extended a rod

16 attached to or forming part of the piston rod 17 of a piston 18 located in the cylinder *a* and movable in the chamber 10. The rod 16 has mounted upon it within the chamber 12, a valve 20, which moves in unison with the piston and controls one and preferably two ports or passages 21, 22 formed in the wall *c* and extended from the rear face of said wall to the outside of the cylinder *a*. The passages 21, 22 form inlet and outlet 60 65 passages for the cylinder *a*, and in the present instance they communicate with hollow bosses 24, 25, extended laterally from the cylinder *a* and forming casings for inlet and outlet check valves 26, 27, preferably made 70 as herein shown and each comprising a metal disk provided with a stem and having a leather facing. The casing 24 for the inlet valve 26 is threaded for connection thereto of a pipe 30, and the casing 25 of the outlet 75 valve 27 is threaded for the connection therewith of a pipe 31.

The inlet valve 26 coöperates with a valve seat formed by the end of a bushing 32 inserted into the hollow boss 24, and said valve 80 is seated by a light spring 33 located within the said hollow boss.

The outlet valve 27 coöperates with a valve seat formed by the end wall of the hollow boss 25, and is held to its seat by a light 85 spring 34 located in the hollow boss 25 and retained therein by a bushing 35, which is inserted into said boss. The wall *c* is preferably provided with a central projecting portion 36 through which the passages 21, 90 22 are extended and which forms a seat for the valve 20. The piston rod 17 is extended through the head *b* of the cylinder *a* and through a hub 37 attached to the head *b*, and is encircled within said hub by a spring 95 38, which bears against the end wall of the hub and at its other end against a shoulder 39 on the piston rod, which latter may be provided at its outer end with a detachable nut or head 40.

The cylinder *a* is represented in Fig. 1 as affixed to the dasher 42 of an automobile 43, which is effected as herein shown by extending the hub 37 through a hole in the dasher and engaging the threaded end of the hub 105 with a nut 44 which bears against a collar 45.

The cylinder *a* has its inlet boss 24 connected with the source of gasoline supply and its outlet boss connected with the motor 110

of the automobile, and in the present case, the inlet boss 24 is connected by the pipe 30 with the pipe 47 leading from the tank 48 to the carburetor 49, which latter is connected by pipe 50 with the manifold 51 of the motor, not shown, and the outlet boss 25 is connected by the pipe 31 with the said manifold.

In operation with the primer herein shown, the piston 18 is moved on its suction stroke in the direction of the arrow 55, by the spring 38, and in the opposite direction by the hand or foot of the operator pressing upon the head 40. On the suction stroke of the piston, gasoline is drawn through the pipe 30, hollow boss 24, passage 21 into the chamber 12, from which it passes into the chamber 10 through the openings 13 in the wall *c*. The inlet check valve 26 is lifted from its seat by the suction of the piston 18.

The valve 20 moves axially with the piston 18 and is seated when the piston is at the end of its suction stroke as represented in Fig. 2. At such time, the inlet check valve 26 is closed and the inlet passage 21 in the wall or head *c* is closed by the valve 20, which also closes the inlet end of the outlet passage 22, and the cylinder *a* is charged with gasoline or other priming fluid, and the parts of the apparatus are in the condition shown in Fig. 2.

When it is desired to prime the motor, the operator pushes upon the head 40 and moves the piston 18 and the valve 20 in the direction of the arrow 60, the valve 20 being thus moved away from its seat 36 so as to connect the outlet passage 22 with the cylinder *a* and permit the gasoline in the latter to be forced by the piston out through the passage 22, hollow boss 25 and pipe 31 into the manifold 51, the outlet check valve 27 being opened by the gasoline forced through the passage 22, as represented in Fig. 3.

On the discharge stroke of the piston, the spring 38 is compressed as represented in Fig. 3, and as soon as the pressure is removed from the head 40, the spring 38 moves the piston on its suction stroke, and gasoline is drawn from the pipe 30 into the cylinder *a* as above described. As the piston is moved on its suction stroke, the valve 20 being attached to it moves therewith toward its seat, so as to cut off the inlet and outlet passages 21, 22 from the cylinder when the piston reaches the end of its suction stroke. On the discharge stroke of the piston, the inlet check valve 26 is seated by its spring 33 assisted by the pressure of the gasoline in the cylinder. It will be observed that the valve 20 when closed, positively cuts off communication between the cylinder *a* and the motor, and practically seals the charge of gasoline in the cylinder and prevents the motor when

running from drawing gasoline from the cylinder. It is preferred to locate the inlet passage 21 in the wall or head *c* and to close the same by the valve 20 when the latter is seated. This arrangement places both the inlet and outlet passages under control of the valve 20 and by loosely mounting the latter upon the rod 16 so as to tilt thereon, the valve can adjust itself to any slight irregularities or unevenness in the valve seat which avoids the necessity of grinding or otherwise nicely finishing the valve seat.

On the other hand, the valve 20 may be sweated or otherwise firmly secured liquid tight on the rod 16, and the valve seat may be ground or otherwise finished to conform to the valve. It is preferred to make the fluid inlet passage 21 in the wall or head *c* and thereby place it under the control of the valve 20, but it is not desired to limit the invention to this particular location of the fluid inlet for the cylinder.

I have herein shown one construction embodying the invention, but it is not desired to limit the invention to the particular construction shown.

An apparatus of the character herein described in which communication between the cylinder and its fluid outlet is cut off by means operatively connected with the piston to be positively moved thereby on the suction stroke of the said piston, is not herein claimed as it forms subject-matter of another application Serial Number 78747 filed by me February 16, 1916.

Claims.

1. In an apparatus of the character described, in combination, a cylinder provided with a wall having an opening extended through it and a passage leading from the rear face of said wall to the side of the cylinder, a piston in said cylinder, a rod attached to the said piston to move therewith and extended through said wall, a valve on said rod movable therewith and co-operating with the rear face of said wall to close the said passage on the suction stroke of said piston, and a spring to move said piston on its suction stroke. 105 110 115

2. In an apparatus of the character described, in combination, a cylinder provided with a wall having an opening extended through it and a passage leading from the rear face of said wall to the side of the cylinder, a piston in said cylinder, a rod attached to the said piston to move therewith and extended through said wall, and a valve on said rod movable therewith and co-operating with the rear face of said wall to close the said passage on the suction stroke of said piston. 120 125

3. In an apparatus of the character described, in combination, a cylinder provided 130

with a wall and with a detachable cap forming with said wall a chamber, said chamber having a fluid inlet and a fluid outlet, and said wall having a passage connecting 5 the said cylinder with said chamber, a piston in said cylinder having its piston rod extended through said wall into said chamber, a valve in said chamber movable with said piston rod and coöperating with said 10 fluid outlet to close the same on the suction stroke of said piston.

4. In an apparatus of the character described, in combination, a cylinder provided at one end with a wall and having communicating with it a chamber located on the 15 opposite side of said wall, an outlet passage in said wall for connecting said chamber and cylinder with the outside of said cylinder, a piston in said cylinder having 20 its piston rod extended through said wall into said chamber, and a valve mounted on said piston rod within said chamber and

coöperating with said outlet passage to close the same on the suction stroke of said piston.

25

5. In an apparatus of the character described, in combination, a cylinder provided with a fluid outlet and with a reciprocating piston, and a valve mounted on the piston rod of said piston and coöperating with said 30 fluid outlet to close the same on the suction stroke of said piston.

6. In an apparatus of the character described, in combination, a cylinder provided with a fluid inlet and with a fluid outlet, 35 a piston reciprocating in said cylinder, and a valve mounted on the piston rod of said piston to move therewith and coöperating with said fluid inlet and outlet to close the same on the suction stroke of said piston. 40

In testimony whereof, I have signed my name to this specification.

FREDERICK O. KILGORE.
